UNITED STATES PATENT OFFICE.

THOMAS G. RAKESTRAW AND ARTHUR E. RAKESTRAW, OF DETROIT, MICHIGAN,
ASSIGNORS OF ONE-FOURTH TO CHARLES C. CANNY, OF DETROIT, MICHIGAN.

STEAM-TRAP.

1,281,835.

Specification of Letters Patent. Patented Oct. 15, 1918.

Application filed January 24, 1918. Serial No. 213,474.

To all whom it may concern:

Be it known that we, THOMAS G. RAKESTRAW and ARTHUR E. RAKESTRAW, citizens of the United States, residing at Detroit, 5 county of Wayne, State of Michigan, have invented a certain new and useful Improvement in Steam-Traps, and declare the following to be a full, clear, and exact description of the same, such as will enable others 10 skilled in the art to which it pertains to make and use the same, reference being had to the accompanying drawings, which form a part of this specification.

Our invention relates to steam traps shown 15 in the accompanying drawings and more particularly described in the following specification and claims.

One of the objects of this invention is to simplify the general construction of apparatus of this description by dispensing with 20 many parts common to the operation of the type of trap employing tilting tanks, which when actuated serve to operate its inlet and discharge valves.

One feature of the invention is the vertical alternating movement of the respective tanks and valves controlling the delivery of water and steam and discharge therefrom, thereby eliminating many of the rocking 25 30 parts necessary to the action of the tilting type of trap.

With the foregoing and other objects in view which will appear as the description proceeds, the invention resides in the combination and arrangement of parts and in the details of construction hereinafter described and claimed, it being understood that changes 35 may be made in the precise embodiment herein described without departing from the 40 spirit of the invention.

In the accompanying drawings:—

Figure 1 is a longitudinal vertical sectional view on line 1—1 of Fig. 2.

Fig. 2 is a cross-sectional view on line 2—2 45 of Fig. 1.

Referring now to the letters of reference placed upon the drawings:

A, denotes a suitable base plate, from 50 which rises a standard B.

C, indicates a rocking arm pivoted to the upper end of the standard.

D, D, indicates a pair of vertically movable tanks connected to the rocking arm by links d.

E, denotes a reciprocating sleeve valve

secured to the under side of each tank at one end, for controlling the delivery of water to and from the tanks.

F, indicates the valve cylinder or casing, 60 bolted to the base-plate.

G, is a pipe having branches leading to each valve cylinder for conducting thereto the water of condensation from a heating system or other condensing surface (not shown).

G', is a check valve adapted to close against the return of the water to the heating system.

H, is a discharge pipe having branches connected with the outlet port of the cylinder 70 for conducting the water from the trap to the boiler (not shown).

I, I, denote reciprocating steam valves similar in construction to the water valves E.

J, J, are the cylinders or casings of said 75 valves secured to the base plate.

K, indicates a pipe having branches leading to the inlet port of each steam valve connecting the steam space of the boiler therewith. K', is an exhaust pipe provided with 80 similar branches leading to the exhaust ports of the steam valve. L, denotes the usual pipe extending upwardly from the steam valve within the tank to deliver steam above the water level therein.

M, is an expansion ring fitted to both the steam and water valves, adapted to seal the respective ports in the valve cylinders upon the valve registering therewith. N, is a suitable packing nut fitted to each valve cylinder 90 to insure against leakage around the valve.

Having indicated the several parts by reference letters the construction and operation of the apparatus will be readily understood.

The trap having been installed at a suitable altitude above the boiler, and the several pipe connections between the heating system and the trap, and between the trap and boiler common to apparatus of this 100 character being properly made—condensation from the heating system is permitted to enter the elevated tank of the trap. Upon the latter filling with water sufficiently to overcome the weight of the depressed tank—105 the elevated tank descends, opening thereby the discharge port through the water valve to the boiler, and simultaneously with the opening of the steam inlet port through the steam valve. Steam having been thus ad- 110

mitted to the tank, the pressure therein is balanced with the boiler pressure permitting the water to flow from the tank by gravity to the boiler.

- 5 While the water is discharging from one tank into the boiler, water from the condensing system (not shown) enters the other tank in the manner just described until its weight again causes the tank to descend
10 thereby forcing the other tank upwardly through the action of the tilting lever C. The steam valve being shifted through the upward movement of the tank, boiler pressure is thereby cut off and the exhaust port
15 opened to relieve the tank of all pressure, that the water of condensation may again enter the tank through valve at its opposite end.
- 20 It will now be apparent that water is alternately discharged by one tank while the other is receiving water from the condensing system, the water being discharged by gravity into the boiler through the alternate admission to the tanks of steam to balance the boiler pressure.

Having thus described our invention, what we claim is:

- 25 1. In an apparatus of the character described, a base, a relatively long standard rising from the base, a substantially V-shaped lever pivoted intermediate its ends to the upper end of said standard for rocking movement thereon, pairs of cylindrical casings rising from the base, upper and lower pipes connecting the casings of each
30 pair and communicating therewith, an inlet pipe connecting the upper pipes, an exhaust pipe connected to the lower pipes, a cylindrical ported valve mounted for reciprocating movement in each of said casings, tanks rigidly connected to the valves of op-

posite pairs of said casings and having communication with the latter through the valves, and connections between the ends of the substantially V-shaped lever and the tanks, whereby the alternate delivery and discharge of water to and from the respective tanks and also the delivery of steam to and the relief of pressure in the tanks is controlled.

50 2. In an apparatus of the character described, a base, a relatively long standard rising from the base, a rocking lever pivoted to the upper end of the standard, a pair of vertically movable tanks connected to said lever, a pair of sleeve valves rigidly connected with the tanks adapted to control the alternate delivery and discharge of water to and from the tanks, a pair of sleeve valves rigidly connected with the tanks adapted to alternately deliver steam to the tank and relieve the pressure therein, valve casings for the respective valves mounted on the base plate and constructed to restrict the valve sleeves to a straight, up and down vertical movement and thereby restrict the tanks to a straight up and down movement, the said casings having inlet and discharge ports controlled by said valves, and suitable pipe connections leading to and from the respective valve casings and connected to the inlet and discharge ports thereof for the delivery and discharge of water and also of steam and the relief of pressure in the tanks.

75 In testimony whereof we sign this specification in the presence of two witnesses.

THOMAS G. RAKESTRAW.
ARTHUR E. RAKESTRAW.
